(57) **CLAIM**

The ornamental design for an air cleaner panel, as shown and described.

DESCRIPTION

FIG. 1 is a front and left side perspective view of the air cleaner panel;

FIG. 2 is a front elevation view thereof;

FIG. 3 is a top plan view thereof;

FIG. 4 is a left elevation view thereof; and,

FIG. 5 is a right elevation view thereof.

No claim is made to ornamentation on the bottom or rear view of the air cleaner panel.

The features shown in broken lines depict environmental subject matter only and form no part of the claimed design.
